UNITED STATES PATENT OFFICE

92,361

DESIGN FOR A RAZOR BLADE

George Robinson McIlhagga, Belfast, Ireland,
assignor to George R. McIlhagga & Company,
Belfast, Ireland

Application February 28, 1934, Serial No. 50,896
In Great Britain November 10, 1933

Term of patent 14 years

To all whom it may concern:

Be it known that I, GEORGE ROBINSON McILHAGGA, a subject of the King of Great Britain, and a resident of the city of Belfast, Ireland, have invented a new, original, and ornamental Design for a razor Blade, of which the following is a specification, reference being had to the accompanying drawing, forming part thereof.

The figure is a plan view of a razor blade, showing my new design.

I claim:

The ornamental design for a razor blade, as shown.

GEORGE ROBINSON McILHAGGA.
